UNITED STATES PATENT OFFICE.

CHARLES F. STOCK, OF PEORIA, ILLINOIS.

BALL-TRAP.

SPECIFICATION forming part of Letters Patent No. 295,302, dated March 18, 1884.

Application filed December 28, 1883. (No model.)

To all whom it may concern:

Be it known that I, CHARLES F. STOCK, of Peoria, in the county of Peoria and State of Illinois, have invented a new and Improved 5 Device for Throwing Targets, of which the following is a full, clear, and exact description.

This invention relates to that class of target-throwing devices known as "clay-pigeon and 10 ball traps," wherein a throwing-arm swinging upon a center is employed; and the invention consists in the employment of a novel device at the outer end of the throwing-arm for holding the target, the same being adapted to retain 15 the target during the swing of the arm and to release it at the proper time for causing it to be properly projected into the air.

Reference is to be had to the accompanying drawings, forming part of this specification, in 20 which similar letters of reference indicate corresponding parts in all the figures.

Figure 1 is a perspective view of a target-throwing device having one form of my new target-holding plate or clip applied thereto, 25 showing in full lines the target-holding clip in the position it occupies when the target is placed in the trap, ready to be thrown, and in dotted lines the position it assumes at the time of releasing the target. Fig. 2 is a sectional 30 elevation of the outer end of the throwing-arm, showing the construction and arrangement of the clip. Figs. 3 and 4 show, respectively, in plan and side elevation a modified form of clip, wherein a spring is used. Fig. 5 shows in side 35 elevation another form of clip wherein a spring is used. Fig. 6 is a perspective view of a clip arranged without a spring, and Fig. 7 is a perspective view of a clip for throwing glass balls or other targets having small orifices.

40 A is the throwing-arm of the trap, to the outer end of which arm my new clip B is hinged. The arm A is secured to the pulley C, which is operated by pulling upon the cord D for rapidly swinging the arm A from the 45 position shown in full lines in Fig. 1 (where it is retained by the tension-spring E) to that shown in dotted lines for throwing the target into the air. The clip B is composed of the bent plate a, which carries the rubber block b, 50 and has hinged to its under side the tongue c,

by which the clip is hinged to the outer end of throwing-arm A, in the slot d thereof upon the pin e. The tongue c is beveled or brought to a point at its lower end, and against its lower pointed end impinges the bent end f' of the 55 friction-spring f, secured to the lower side of the arm A, as shown clearly in Fig. 2. The pressure of the spring f upon the lower end of the tongue c may be regulated by the screw g.

When the clip B is arranged for use, the 60 tongue c will be brought to the position shown in dotted lines in Fig. 2, where it will be held with considerable force by the spring f. The plate a will then be swung around upon the swivel or hinge-pin a', so that the block b will 65 stand parallel with the arm A, as shown in full lines in Fig. 1. The arm A will now be "set"—that is, swung back, so that the stud a' thereof will be engaged by the tension-spring E. The target F, which is a cupped clay target, 70 (shown in dotted lines,) will then be placed upon the weighted portion A' of the body B' of the target against the lip C' and over the block b or lip of the clip, as illustrated in Fig. 1. Now upon pulling upon the cord D the 75 arm A will be detached from the tension-spring E and swing rapidly to the position shown in dotted lines in Fig. 1, where it will be suddenly stopped by the reverse action of the cord D upon the pulley C. As the arm A 80 swings around the target F will be carried with it, being held by the clip B. The centrifugal force of the target, imparted by the rapid swinging of the arm A, will gradually turn the plate a upon the hinge-pin a', as the 85 arm A proceeds until the direction of the centrifugal force comes in line with the slot d in the outer end of the arm A, whereupon the lower end of the tongue c will be forced back of the friction-spring f, which will permit the 90 plate a to drop down to the position shown in full lines in Fig. 2 and in dotted lines in Fig. 1, and thus release the target. The slot d being made in the line of the length of the arm A, it will be seen that the clip B will not 95 release the target until the arm A reaches the end of its swing, so that the target will receive all of the propulsive force of rapid swinging of the arm, save that which is lost in overcoming the friction of the spring f.

In the form of clip shown in Figs. 3 and 4, instead of hinging the main plate *a* to the tongue *c* and providing the plate with a block of rubber, I attach the plate rigidly to the tongue *c* and pivot upon the plate the button *h*, which turns with the centrifugal force of the target and releases the target at the proper time by the dropping of the main plate to an inclined position at the end of the sweep of the arm *A* of the same, as in the form of clip shown in Figs. 1 and 2, the tongue *c* turning in slot *a* against the action of the spring *f*. In place of the button *h* a plain stud might be used with good results; but with the button there is no danger of breaking the rim of the target, as might be the case with the stud.

In the form of clip shown in Fig. 5 the target is held to the throwing-arm *A* by the plate *j*, attached to the upper end of the bolt *k*, which passes through the arm *A*, and has the coiled spring *l* placed upon it, so as to act between the under side of the arm *A* and the nut *i* on lower end of the said bolt *k*. In the upper side of the arm *A* is formed the transverse slot *m*, into which the spring *l* suddenly draws the plate *j* when the target is to be released. In setting this form of clip the plate *j* will be lifted out of the slot *m* against the tension of the spring *l* and turned across the slot *m* parallel with the length of the arm *A*, and the rim of the target will be placed over the plate *j*, as over the button *h* and block *b* in the forms of clips above described. As the arm *A* swings around the centrifugal force of the target will turn the plate *j* until it comes parallel with the slot *m*, whereupon the spring *l* will draw it quickly into the slot *m* and thus release the target.

In the form of clip shown in Fig. 6 the target is held to the throwing-arm *A* by the block of rubber *b*, held in the bent plate *o*, which is hinged to the plate *p*, pivoted upon the upper side of the arm *A*. To the under side of the arm *A* is secured the slotted plate *q*, the slot of which coincides with the slot *d* made in the arm *A*. The edge of the plate *q* is rounded and projects beyond the sides and end of the arm *A*, as shown at *q'*, and the under side of the bent plate *o* is formed or provided with the toe *o'*, which is adapted to rest against the outer edge of the plate *q*, as shown, for hold-

ing the bent plate *o* and rubber block *b* in position parallel with the arm *A* for receiving and holding the target. The edge of the target to be thrown will be placed, as in the other forms, over the block *b*, which will hold the target until its centrifugal force swings the plates *p* and *o* around in line with the slot *d* in the arm *A* and the slot in the plate *q*, whereupon the toe *o'* will drop into the said slots and permit the plate *o* and block *b* to drop to an inclined position and thus release the target.

The form of clip shown in Fig. 7 is to all intents and purposes like that shown in Fig. 6, except that in place of the bent plate *o* and rubber block *b* the plate *p* has hinged to it the small toe-plate *s*, which is formed or provided with the pin *t*, which is adapted to have placed upon it glass balls or other targets having small orifices suitable to receive the said pin. The pin *t*, by means of the plate *q* and toe *o'*, is held in vertical position when the plate *p* is turned at right angles to the throwing-arm *A*, as shown, in which position it will hold the glass-ball target, and will continue to hold the same during the swinging movement of the arm *A*, until the centrifugal force of the target swings the plate *p* around, so that the toe *o'* coincides with the slot in the plate *q* and the slot *d* in the arm *A*, whereupon the pin *t* will drop to a position nearly parallel with the arm *A*, and thus release the target.

Having thus described my invention, what I claim as new, and desire to secure by Letters Patent, is—

1. The combination, with the throwing-arm of a target-throwing device, of a clip for holding the target, arranged to automatically drop below the upper surface of the throwing-arm for releasing the target, substantially as described.

2. The target-holding clip, consisting of the pivoted plate *p*, having the plate *o*; provided with toe *o'*, hinged to it, in combination with the slotted plate *q*, all adapted to be operated substantially as described.

CHARLES F. STOCK.
